UNITED STATES PATENT OFFICE.

JOHN C. A. ANDERSON, OF CHICAGO, ILLINOIS, ASSIGNOR TO CONCEALED DOOR CHECK COMPANY OF DELAWARE, OF CHICAGO, ILLINOIS.

DOOR-CHECK.

1,044,723.

Specification of Letters Patent. Patented Nov. 19, 1912.

Application filed January 20, 1910. Serial No. 539,161.

To all whom it may concern:

Be it known that I, JOHN C. A. ANDERSON, citizen of the United States, residing at Chicago, in the county of Cook and State of Illinois, have invented a certain new and useful Improvement in Door-Checks, of which the following is a full, clear, concise, and exact description, reference being had to the accompanying drawings, forming a part of this specification.

My invention relates to door checks, and more particularly to liquid door checks, and has for its object the provision of an improved door check which can be concealed in the door, and in which the operating parts have been reduced to a minimum.

Generally speaking, my invention comprises a casing, within which the liquid is placed, which casing is countersunk either in the door or the door jamb, as the case may be, and within which casing a cylinder is movable, which operates in connection with a stationary piston, means being provided to permit liquid or fluid to flow to the cylinder as the door opens, and adjustable means being provided to permit egress of the fluid or liquid from the cylinder as the door closes.

My invention further contemplates means whereby the egress of the liquid from the cylinder, in the course of each operation, is automatically adjusted, so that the door may move more slowly, as it reaches its closing point, and when very near to the closing point, additional means are brought into operation, which permit more rapid egress of liquid from the cylinder.

I will describe my invention more in detail by reference to the accompanying drawing illustrating the preferred embodiment thereof, in which—

Figure 1 represents a horizontal sectional view of my improved door check, in association with a hinge, and as countersunk in the door. Fig. 2 is a vertical sectional view of the valve-adjusting and link mechanism. Fig. 3 is a top view, showing the valve-controlling mechanism in a different operative position; and Figs. 4 and 5 are details of construction.

In describing my invention, I will describe it specifically with relation to the drawing, but of course, I do not limit myself on this account to the specific terms which may be

employed in connection with this description, as modifications of the invention will be readily apparent.

Referring more particularly to Fig. 1, I have shown a door 1, as mounted by means of the hinged plates 2, 3, to a door jamb 4. My improved door check is countersunk in the door 1, so that it is concealed from view, and consists of a liquid inclosing casing 5, united by a waterproof connection to a cylindrical tube 6. The casing 5, at the other end, is hermetically sealed by a removable cap 7, which removable cap has a screw-threaded arrangement with the casing 5 through the interposition of suitable packing 8. Within the casing 1 provide a cylinder 9, which cylinder has a flange 10, through which holes 11 are provided. The flange 10 and the tube 6 inclose between them an extensible or draw-spring 12, the tendency of which is to force the cylinder to the right of the illustration.

Within the cylinder 1 provide a piston 13, which piston is provided with suitable packing appliances 14, and which has a bore 15, through which liquid may enter within the cylinder 9. A check valve 16 controls a port 17, which governs the flow of liquid.

When the cylinder is moved tending to form a partial vacuum therein, the liquid raises the valve 16 and enters the cylinder through port 17. The notches 18 prevent displacement of the valve 16. The liquid in the casing 5 should always be of a height sufficient to control the projecting port 17, with its associated valve.

The cylinder 9, by means of a union 19, is secured to an auxiliary cylinder 20, which cylinder, as is more clearly apparent from Fig. 2, carries a pin 21, which pin is rotatably mounted within the cylinder 20, and is permanently secured to a forked arm 22, which forms part of a link 23, which link is pivotally secured in a door jamb, by means of a bolt 24. When the door is opened, and the link 23 swings around its pivotal support 25, the pin 21 moves with the link and rotates within its support in the cylinder 20, but carries said cylinders 9 and 20 to the left, against the action of the draw-spring 12. This action permits the liquid to flow through the port 17 into the cylinder 9. After the door is opened and released by the opener, the check valve

16 closes, and the liquid is forced through the opening provided in the port 26, which is controlled, in this instance, by a needle valve 27. The liquid thus flowing through 5 the port 26 returns to the casing through the aperture 28. The amount of liquid flowing through the port 26 regulates the speed with which the door closes, and this is absolutely under the control of the needle 10 valve 27. The needle valve 27 is mounted on the stem 29, which is screw-threaded within the cross-head 30, which cross-head is held in its position toward the right by means of a very strong leaf spring 31.

15 The object of thus yieldingly mounting the needle valve 27 is for the purpose of preventing breakage of the apparatus should any one attempt to forcibly close the door more rapidly than the spring 12 would 20 close the door, in which case the pressure would cause the needle valve to be opened to a greater extent against the pressure of the spring 31. The adjustment of the valve 27 is accomplished by a set-screw 32, which 25 impinges against a cam 33, which cam is a part of the pin 21, and which cam is more clearly illustrated in Figs. 1 and 3.

It will be seen that a turn of the adjustment screw 32 draws the needle valve in or 30 out of the port 26, thus to give a permanent adjustment to the needle valve. In order to obtain an adjustment of this needle valve which shall be automatically varied at each stroke, the cam 33 is utilized, and its flaring 35 faces, as will be seen, open the valve 27, when the door is opened, so that when the door is released, the valve 27 is opened farther than when the door is closed, or nearly closed. As the door begins to close, 40 the set screw 32 slides over the rotating cam 33, and by virtue of the spring 31, the needle valve 27 is gradually closed as the door closes, although this needle valve is not entirely closed. From this, it will be seen 45 that the movement of the door is slower and slower as the door reaches its closing point. A projection 34 may be provided upon the piston 13, which engages the needle valve 27 when the door is very nearly shut, to 50 open this valve rapidly, whereby to get added effort so as to give the door a sudden jerk when it is about at its closing point. It will be seen that the set screw 32 can be readily adjusted when the door is open, as 55 will be apparent from Fig. 3. I so arrange the apparatus and the cap 7 that when this cap is removed, the operating parts of the door check,—that is, the cylinder, piston, draw spring and the link 23 can be drawn 60 out of the right hand end by releasing the pin 25, thus to make the device extremely accessible.

While I have herein shown and particularly described the preferred embodiment 65 of my invention, I do not limit myself to

the precise construction and arrangement shown therein, but

Having thus described my invention, what I claim as new and desire to secure by Letters Patent is:

1. In combination, a door and a liquid door check having an inclosing casing, a cylinder movable therein, a link pivotally secured to said cylinder and adapted to move said cylinder when the door is moved, a piston for said cylinder, and a valve movable with the cylinder to control the gradual efflux of liquid from said cylinder. 70

2. In combination, a door and a liquid door check having an inclosing casing, a cylinder movable therein, a link pivotally secured to said cylinder and adapted to move said cylinder when the door is moved, a piston for said cylinder, a valve movable with the cylinder to regulate the efflux of liquid 85 from said cylinder, and means for automatically adjusting said valve as the door moves. 80

3. In combination, a door and a liquid door check having an inclosing casing, a cylinder movable therein, a link pivotally secured to said cylinder and adapted to move said cylinder when the door is moved, a piston for said cylinder, a valve movable with the cylinder to control the efflux of liquid 90 from said cylinder, and means including a cam for automatically adjusting said valve as the door moves. 95

4. In combination, a door and a liquid door check having an inclosing casing for carrying liquid, a cylinder movable therein, a link pivotally secured to said cylinder and adapted to move said cylinder when the door is moved, a piston for said cylinder, a needle valve movable with the cylinder to control the efflux of liquid 100 from said cylinder, and means including a cam for automatically adjusting said valve as the door moves. 105

5. In combination, a door and a liquid door check having an inclosing casing, a cylinder movable therein, a link pivotally secured to said cylinder and adapted to move said cylinder when the door is moved, a piston for said cylinder, a valve movable with the cylinder, and means including a cam for automatically adjusting said valve as the door moves, said link serving to control the operation of said cam. 110

6. In combination, a door and a liquid door check having an inclosing casing, a cylinder movable therein, a link pivotally secured to said cylinder and adapted to move said cylinder when the door is moved, a piston for said cylinder, a valve movable with the cylinder to regulate the efflux of liquid 120 from said cylinder, and means for yieldingly holding said valve in place. 125

7. In combination, a door and a liquid door check having an inclosing casing, a 130

cylinder movable therein, a link pivotally secured to said cylinder and adapted to move said cylinder when the door is moved, a piston for said cylinder, a valve movable with the cylinder to regulate the efflux of liquid from said cylinder, and a spring for yieldingly holding said valve in place.

8. In combination, a door and a liquid door check having an inclosing casing, a cylinder movable therein, a link pivotally secured to said cylinder and adapted to move said cylinder when the door is moved, a piston for said cylinder, a valve movable with the cylinder to control the efflux of liquid from said cylinder, and means for making permanent adjustments of said valve.

9. In combination, a door and a liquid door check having an inclosing casing, a cylinder movable therein, a link pivotally secured to said cylinder and adapted to move said cylinder when the door is moved, a piston for said cylinder, a valve movable with the cylinder to control the efflux of liquid from said cylinder, and an adjusting screw for making permanent adjustments of said valve.

10. In combination, a door and a liquid door check having an inclosing casing, a cylinder movable therein, a link pivotally secured to said cylinder and adapted to move said cylinder when the door is moved, a piston for said cylinder, a valve movable with the cylinder to control the efflux of liquid from said cylinder, and means for causing an increased opening of said valve when the door reaches its nearly shut position.

11. In combination, a door and a liquid door check having an inclosing casing, a cylinder movable therein, a link pivotally secured to said cylinder and adapted to move said cylinder when the door is moved, a piston for said cylinder, means controlled by

a valve for permitting liquid to unobstructedly enter said cylinder as the door is opened, and a valve movable with the cylinder to regulate the efflux of liquid from said cylinder.

12. In combination, a door and a liquid door check having an inclosing casing, a cylinder movable therein, a link pivotally secured to said cylinder and adapted to move said cylinder when the door is moved, a piston for said cylinder, a valve movable with the cylinder to regulate the efflux of liquid from said cylinder, and means for making permanent adjustments of said valve, accessible only when the door is open.

13. In combination, a door and a liquid door check having an inclosing casing, a cylinder movable therein, a link pivotally secured to said cylinder and adapted to move said cylinder when the door is moved, a piston for said cylinder, a valve movable with the cylinder to regulate the efflux of liquid from said cylinder, and an adjusting screw for making permanent adjustments of said valve, accessible only when the door is open.

14. In combination, a door and a liquid door check having an inclosing casing, a cylinder movable therein, a link pivotally secured to said cylinder and adapted to move said cylinder when the door is moved, a piston for said cylinder, a valve movable with the cylinder to control the efflux of liquid from said cylinder, and a stop for causing an increased opening of said valve when the door reaches its nearly shut position.

In witness whereof I hereunto subscribe my name this 24th day of December A. D. 1909.

JOHN C. A. ANDERSON.
